UNITED STATES PATENT OFFICE.

CHARLES FRANCIS HIGGINS, OF LONDON, AND JAMES GUNN, OF BARROW-IN-FURNESS,
ENGLAND.

EJECTOR.

1,413,733.

Specification of Letters Patent. Patented Apr. 25, 1922.

Application filed November 8, 1919. Serial No. 336,612.

To all whom it may concern:

Be it known that we, CHARLES FRANCIS HIGGINS and JAMES GUNN, both subjects of the King of Great Britain, and residents of 5 London, England, and Barrow-in-Furness, England, respectively, have invented certain new and useful Improvements in Ejectors, of which the following is a specification.

This invention relates to apparatus for 10 withdrawing fluids by means of ejectors.

When discharging aerated vapour or gas against a pressure by means of an ejector and particularly a steam operated ejector, it is known that unless the combining tube in 15 to which the jet discharges is sufficiently filled, the uniformity and continuity of flow through the tube is disturbed by reason of the increased tendency to back flow, and the discharge becomes erratic and intermittent 20 thereby causing instability of the ejector; and the greater the pressure difference under which the ejector works, the greater will be the degree of instability from this cause.

To obviate this defect it has been suggested to introduce from without the system 25 additional air or other elastic fluid into the system and with the object of reducing or checking the expansion of the operating fluid passing through the expanding nozzle 30 or nozzles at starting additional fluid has been admitted to the nozzle or nozzles at one or more intermediate points along its or their length. The present invention differs from the former of these proposals in that 35 the elastic fluid employed is essentially fluid already contained in the system and it differs from the latter proposal in that according to our invention the fluid is by-passed from some suitable position within the system 40 to the suction system from which the steam jet withdraws and not to the expanding nozzle at all.

Our invention therefore consists of a 45 means for stabilizing ejectors comprising a by-pass circuit for conducting fluid from some suitable position within the system to the suction system or convergent portion of the combining tube of the ejector to be stabilized.

50 A convenient method of carrying the invention into practice is to provide the by-pass circuit on the ejector itself so that a circulation of elastic fluid takes place from the throat of the ejector or thereabouts back 55 again to a position behind the throat. This

by-pass circuit may be provided with a throttle device for varying the area of the by-pass and in addition to or in lieu of this throttling device means may be provided for varying the position or width of the opening 60 or openings in the wall of the throat and through which the fluid passes to the suction side of the ejector.

According to another arrangement we may cause steam or aerated vapour or gas already 65 in the system to by-pass from one part of the system to another, the device by which the by-pass is effected being controlled by some suitable form of valve. This valve may be an automatic valve adapted to open 70 and close in accordance with the pressure or degree of vacuum in some suitable part of the system, such for instance, as in an intermediate condensing receiver.

In Fig. 1 of the accompanying drawings 75 we have illustrated diagrammatically an ejector constructed in accordance with our invention.

Fig. 2 is a similar view illustrating a 80 modified form of ejector.

Fig. 3 is a longitudinal section showing another form of our invention, while Fig. 4 is a transverse section on line A—A of Fig. 3.

Upon reference to Fig. 1 it will be seen 85 that the ejector is provided with a by-pass circuit constituted by the passage 2 which leads from the opening 3 in the throat back to a position 1 behind the throat.

It may be desirable and advantageous in 90 some cases to provide for varying the position or area of the opening in the throat, and this may be accomplished in the manner indicated in Fig. 2. In this case the throat comprises the sleeves 4 and 5 which are slid- 95 able upon the fixed portions 6 and 7, and it will be readily seen that by alteration of the positions of these sleeves 4 and 5 both the width of the throat opening 3 and its position can be adjusted to suit the requirements of 100 any particular case.

In Figs. 3 and 4 we have shown a further 105 constructional form of our invention as applied to an ejector. In this case the by-pass circuit is constituted as before by the passage 2 which leads from an opening 3 in the throat back to a position 1 behind the throat, adjustment and control being provided for by means of an annular throttle valve 8 operated from the shaft 9 through an eccentric 110

2
pin 10, so that the annular valve 8 can be partially rotated so as to bring the ports 12 more or less into coincidence with the ports 12^a leading into the passage 2. In this case it will be seen that there is facility for varying the effective area of a fixed throat opening.

What we claim and desire to secure by Letters Patent is:—

1. Means for stabilizing an ejector comprising a by-pass passage leading from a single opening located essentially in the throat of the ejector to the suction side or convergent portion of the combining tube of said ejector substantially as specified. 25
- 10 2. Means for stabilizing an ejector comprising a by-pass passage leading from a single opening located essentially in the throat of the ejector to the suction side or convergent portion of the combining tube of said ejector and a valve for adjusting the position of said throat opening longitudinally of said ejector substantially as specified. 30
- 15 3. An ejector comprising a steam jet and combining tube and a by-pass passage lead- 35
- 20 ing from a single opening in the throat of the ejector to a port located in the wall of the convergent portion of the combining tube behind said throat substantially as specified. 40
- 25 4. Means for stabilizing an ejector comprising a by-pass passage leading from a single opening located essentially in the throat of the ejector to the suction side or convergent portion of the combining tube of said ejector and means for adjusting the position of said throat opening longitudinally of said ejector substantially as specified. 45
- 30 5. Means for stabilizing an ejector comprising a by-pass passage leading from a single opening located essentially in the throat of the ejector to the suction side of the combining tube of said ejector and means for adjusting the position of said throat opening longitudinally of said ejector and means for varying the effective area of said throat opening substantially as specified. 45

In witness whereof we affix our signatures.
CHARLES FRANCIS HIGGINS.
JAMES GUNN.
